Victor J. Evans,
ATTORNEY

UNITED STATES PATENT OFFICE.

AUGUST WILLENBROCK, OF RICHMOND HILL, NEW YORK, ASSIGNOR OF ONE-HALF
TO FREDERICK C. HAYES, OF BATTLE CREEK, MICHIGAN.

VALVE MECHANISM FOR INTERNAL-COMBUSTION ENGINES.

Application filed September 27, 1920. Serial No. 412,942.

To all whom it may concern:

Be it known that I, AUGUST WILLENBROCK, a citizen of the United States, residing at Richmond Hill, in the county of Queens and State of New York, have invented new and useful Improvements in Valve Mechanism for Internal-Combustion Engines, of which the following is a specification.

10 This invention relates to improvements in valve mechanism for internal combustion engines, and one of the principal objects is to provide a simple and efficient disk valve.

15 Another object is to provide improved baffling and disintegrating means for the fuel.

Another object is to provide an improved oiling system.

20 Another object is to provide a spring pressed valve seat.

With these and other objects in view, the invention consists in certain novel construction and combination and arrangement of parts, the essential features of which are set forth in the following description, and particularly pointed out in the appended claims, and one embodiment of which is shown in the accompanying drawing comprising two sheets, in which:—

30 Figure 1 is a vertical sectional view of a cylinder of an internal combustion engine provided with my improved valve mechanism.

Figure 2 is a view taken substantially in line 2—2, of Figure 1.

Figure 3 is a detail view of the valve per se.

Referring to the drawing in detail, 1 represents the cylinder of an internal combustion engine provided with the usual piston 2 and intake port 3.

40 Mounted in the intake port 3 is a member 4 mounted for movement longitudinally of the cylinder and provided with expansion rings 5 for sealing contact with the sides of the intake 3. The member 4 is surrounded by a spring 6 bearing at its lower end against the cylinder and at its upper end against a shoulder 7 of member 4 and tending constantly to force said member 4 outwardly. Member 4 is provided at its outer end with a curved face 8 and has a plurality of oil ducts 9 leading to said face 8.

50 The cylinder head is shown at 10—10^a and is in two parts provided with leads 11 and

12, the first of which connecting with the intake manifold 13 and the lead 12 connecting with the exhaust manifold. It will be seen that the intake lead 11 has several sharp turns which baffle the air and gas and cause 60 a more complete mixture.

Rotatably mounted in bearings in the cylinder head and in a bracket 14, is a valve shaft 15 which may comprise several parts joined together by universal joints as at 16. 65 This shaft may be driven by any suitable positive means, as, for instance, by a sprocket wheel 17 and chain 18.

A valve disk 19 is secured on shaft 15 and is provided in its edge with intake and exhaust ports 20 and 21, respectively, which are adapted to register with the respective leads 11 and 12 and connect the same with the lead 22 through the member 4. The cross-sectional area of the exhaust passage 75 is in all places at least as great as the cross-sectional area of the lead 22 so as to permit of rapid expulsion of the burned gases.

A cone 23 of foraminous material is seated in the inner end of the lead 22. The 80 purpose of this element is to break up any fuel which may tend to condense in passing through the intake passage.

In combustion engines of the rotary valve type, there has been experienced considerable difficulty in securing a tight seating of the valve against the cylinder intake, so that it has been difficult to obtain the proper compression. In the above described device the face 8 is pressed by spring 6 into such 90 intimate contact with the edge of the disk 19 that a tight seal is constantly maintained. And, further, the valve and the face 8 grind against each other so as to produce a perfect fit. 95

The oiling system includes a lead pipe 24 from which the oil is forced under pressure into a well 25. As the oil rises in well 25 it is forced through ducts 9 against the face of the disk 19. The disk is provided with a groove 26 which is adapted to receive a quantity of oil from ducts 9 and distribute it around the surface of the bearing of disk 19 in number 10. When the oil rises in well 25 to a point above an outlet pipe 27, it 100 flows into said outlet pipe and is conducted away thereby.

While I have described what I deem to be the most desirable embodiment of my invention, it is obvious that many of the de- 110

tails may be varied without in any way departing from the spirit of my invention, and I therefore do not limit myself to the exact details of construction herein set forth nor to anything less than the whole of my invention limited only by the appended claims.

What I claim as new and desire to secure by Letters Patent is:—

- 10 1. In combination with the rotatable valve disk of an internal combustion engine, of a bearing therefor, a member having a seat for said disk, means for normally holding said member seated against the periphery 15 of said valve disk, a well disposed below said seat, an inlet pipe leading to said well for supplying oil thereto, openings communicating with said well and said seat, a groove formed in the periphery of said 20 valve disk for register with the openings in

said member whereby to distribute oil about said bearing upon rotation of the valve disk, and an outlet pipe leading from said well for carrying off oil from said well when the same reaches a predetermined level.

25

2. In combination with the rotatable valve disk of an internal combustion engine, of a bearing therefor, a member having a seat for said disk, means for normally holding said member seated against the periphery 30 of said valve disk, a well disposed below said seat, openings communicating with said well and said seat, a groove formed in the periphery of said valve disk for register with the openings in said member whereby 35 to distribute oil about said bearing upon rotation of the valve disk.

In testimony whereof I have affixed my signature.

AUGUST WILLENBROCK.
